CLAIM

The ornamental design for a display screen or portion thereof with graphical user interface, as shown and described.

DESCRIPTION

THE FIGURE is a front view of a display screen or portion thereof with graphical user interface showing the new design.

The outer perimeter broken lines in the FIGURE depict a display screen or portion thereof and form no part of the claimed design. The remaining broken lines in the FIGURE depict portions of a graphical user interface and form no part of the claimed design.

1 Claim, 1 Drawing Sheet
